Inventor:
Charles L. Fitch,
by his attorney,
Charles R. Searle,

UNITED STATES PATENT OFFICE.

CHARLES L. FITCH, OF NEW YORK, N. Y.

HAIR-CURLER.

1,338,687.

Specification of Letters Patent.

Patented May 4, 1920.

Application filed October 15, 1919. Serial No. 330,755.

To all whom it may concern:

Be it known that I, CHARLES L. FITCH, a citizen of the United States, residing in the city of New York, borough of Manhattan, 5 in the county and State of New York, have invented a certain new and useful Improvement in Hair-Curlers, of which the following is a specification.

The invention relates to curlers in which 10 the hair is wound upon a shell or tube heated by a rod thrust therein, and the object of the invention is to provide a simple, inexpensive and easily operated device of this character, in which the tress or lock of hair 15 to be treated may be securely held in the closely wound condition while supplying heat to the shell, and in which the danger of soiling or singeing the hair during the curling operation is avoided.

20 The invention consists in certain novel features and details of construction by which the above objects are attained, to be hereinafter described and claimed.

25 The accompanying drawings form a part of this specification and show an approved form of the invention.

Figure 1 is a side elevation of the curler with the heating rod engaged in the shell.

Fig. 2 is a corresponding plan view.

30 Fig. 3 is a transverse section taken on the line 3—3 in Fig. 1.

Fig. 4 is an elevation of the rod alone.

Fig. 5 is a vertical longitudinal section through the shell alone.

35 Similar letters of reference indicate the same parts in all the figures.

A is a cylindrical tube or shell of thin sheet metal formed by rolling a strip into tubular form, open at the ends and with the 40 edges of the strip abutted along the upper face of the center line. The shell is cut squarely across at the front end and notched or cut away on the upper face at the rear to provide an offset platform A¹ having side flanges A², extending in alignment with the body of the shell.

45 B is a narrow strip of spring metal pivotally joined to the shell A at the front end by a transverse rivet A³, or otherwise, 50 tending forwardly and downwardly and thence rearwardly along the under face of the shell in arched form, terminating in a tongue B¹ extended forwardly and adapted to lie upon the platform A¹ between the

flanges A². The strip serves as a spring 55 clamp adapted to engage a tress of hair wound upon the shell and hold it yieldingly but firmly in the wound condition.

C is a metal rod adapted to be received in the shell, and equipped with a handle C¹ 60 of wood or other heat insulating material. The rod is designed to be heated in a gas flame or otherwise and thrust into the shell from the rear in the heated condition.

In using the curler the spring clamp B 65 is opened by an upward movement of the free end to raise the tongue B¹ above the flanges A², as shown in dotted lines at b in Fig. 5, and is then forced sidewise, as shown by the dotted lines at b¹ in Fig. 2, to 70 clear the platform A¹ and flanges A² and permit the clamp to swing downwardly on its hinge A³, as indicated by the dotted lines at b² in Fig. 5. The tress or lock of hair to be treated is then wound upon the shell by 75 rolling the latter and is secured by reengaging the tongue B¹. The heated rod C is then inserted in the shell and aids by its heat in the curling operation as usual.

The frictional engagement of the rod 80 against the tongue B¹ is sufficient to hold the rod against accidental displacement when inserted.

When the rod has cooled it is withdrawn 85 and the clamp disengaged and the tress unwound from the shell, or the latter may be kept in position as long as desired. A plurality of shells may thus be used with one or more rods and the tresses held for long periods in the wound condition.

90 As the shell is not exposed to the heating flame its surface is easily kept clean and bright and in condition for service, and as the heated rod is never in direct contact with the hair, danger of burning is eliminated.

95 In order to permit the heat of the rod to act quickly on the tress the shell is preferably provided with a number of perforations a through which the heat may pass 100 directly to the hair while the shell is absorbing heat by contact and radiation from the rod.

105 Modifications may be made in the forms and proportions of the parts without departing from the invention, and parts may be used without the whole. The perforations a may be omitted, and the clamp B may be

varied or other means employed to hold the tress in place on the shell during the treatment.

I claim:—

- 5 1. In a device of the character set forth, a shell having perforations therein and formed at one end with an offset platform, a yielding clamp hinged to said shell at one end and separably engaged therewith at 10 the other end, and a rod independent of said shell and adapted to be removably received in said shell, said clamp coöperating with said rod and platform.
- 10 2. The hair curler described comprising a

cylindrical shell having perforations there- 15 in and an offset platform, a yielding clamp hinged to said shell at one end and having a tongue arranged to engage said shell separably at the other end, and a rod independent of said shell and adapted to be remov- 20 ably received in said shell, said tongue ar- ranged to engage said rod frictionally and hold said rod in place yieldingly in said shell.

In testimony that I claim the invention 25 above set forth I affix my signature.

CHARLES L. FITCH.
